UNITED STATES PATENT OFFICE.

SAMUEL V. TENCH, OF LANSFORD, PENNSYLVANIA.

PLUNGER FOR JIGS.

1,085,509.

Specification of Letters Patent.

Patented Jan. 27, 1914.

Application filed February 5, 1913. Serial No. 746,307.

To all whom it may concern:

Be it known that I, SAMUEL V. TENCH, a citizen of the United States, and a resident of Lansford, county of Carbon, State of Pennsylvania, have invented certain new and useful Improvements in Plungers for Jigs, of which the following is a specification.

My invention relates to improvements in plungers adapted for use in jigs which are employed for the separation of mineral substances having different specific gravities. I have illustrated my invention as applied to a jig adapted for the separation of coal from slate.

One object of my invention is to provide a construction of plunger adapted for use in a jig having means whereby it will automatically adjust itself to the size of the compartment in which it operates independently of the worn condition of its edges due to a long continued usage or other causes.

Other objects and advantages of my invention will be referred to hereinafter or will be apparent from the description.

My invention comprehends the construction and arrangement of parts as illustrated in the accompanying drawings and as hereinafter described in detail and specifically pointed out in the claims. It should be understood, however, that changes in the details of construction may be made within the scope of the claims without departing from my invention.

In order that my invention may be more readily understood and its advantages appreciated reference should be had to the accompanying drawings, in which,—

Figure 1 is a transverse vertical sectional view of a jig showing a plunger embodying my invention in side elevation, Fig. 2 is a top plan view of such plunger with its piston rod removed and also showing a portion thereof broken away and in section, Fig.

Fig. 3 is a transverse sectional view of the plunger taken on the line 3—3 of Fig. 2, Fig. 4 is a transverse sectional view taken on the line 4—4 of Fig. 2, Fig. 5 is a top plan view of a modified construction of plunger with the piston rod removed and with a portion of the said plunger broken away and in section, Fig. 6 is a transverse sectional view taken on the line 6—6 of Fig. 5, Fig. 7 is a view showing a top plan of another modified construction of plunger with the piston rod removed, a portion of the said plunger

being broken away and shown in section and the said view also showing guide posts in transverse section at the corners of said plunger, and Fig. 8 is a transverse sectional view taken on the line 8—8 of Fig. 7.

Referring to the drawings, 1 designates a tank having a discharge opening 2 in its bottom to permit the discharge of water and sediment from the said tank, the said tank being partially filled with water 3 as indicated. The upper portion of the tank is divided by means of a partition 4 into two compartments 5 and 6 in the latter of which a plunger 7 operates.

8 designates grate bars extending from the partition 4 across the compartment 5 to the side of the tank 1.

9 designates an agitator for agitating the material placed upon the grate bar 8 to facilitate the separation of the portions of such material having different specific gravities as, for instance, coal and slate.

The material of heavier specific gravity is discharged from the opening 10 and the material of lighter specific gravity is discharged through the opening 11. For instance, if the apparatus is used to cause the separation of the slate from the coal the former is discharged through the opening 10 while the latter, that is, the coal, is discharged through the opening 11.

The plunger consists of a plate 12 of metal or other suitable material, the under side of which is hollow as indicated at 13, in Fig. 3, leaving what may be termed shoulders or flanges 15 at the outer under edge portions of the plate which surround the hollowed out or recessed portion 13. For the purpose of strengthening the plate cross ribs 16 are provided. The outer upper edges of the plate 12 are grooved or rabbeted as indicated at 20 to form seats for the bearing bars 21. The formation of the grooves 20 in the outer edges of the plate 12 provides the said plate with a flange 22 extending entirely around the same. The bearing bars 21 consisting of wood or other suitable material are held in place in the grooves 20 by means of a plate 23 which is secured to the plate 12 by means of nuts 24 secured upon the upper ends of bolts 25.

As illustrated the width and length of the plate 23 are the same as the corresponding dimensions of the plate 12. The central portion of the plate 23 is cut away as indicated at 26 for the purpose of reducing

the weight of the plunger. The outer edge portions of the plate 12 are provided with passage ways 27 which extend from the hollow or recess 13 in the under side of said plate and communicate with the grooves 20 formed in the outer edges of the said plate. The outer ends of the said passage ways 27 terminate against the inner edges of the bars 21. The ends of the bars 21 overlap each other in the manner indicated at 30 in Fig. 3 of the drawings. The plunger is secured to the lower end of the piston rod 31 by means of screw threaded bolts which engage holes 32 in the top of the plate 12. 15 The said piston rod is reciprocated in any suitable manner and by any suitable means. The reciprocating movement of the plunger 6 in its compartment 6 causes a movement of the water 3 in the tank 1 up and down 20 in the compartment 5. As the plunger moves downwardly the water rises in the compartment 5 and as the plunger moves upwardly the water in the tank follows it so that it rises in the plunger compartment 6 and is lowered in the other compartment 25 5. Such a movement of the water causes agitation of the material to be separated which is located above the grate bars 8 which agitation is increased by the oscillatory movement of the agitating member 9 whereby the lighter constituents of the material to be separated escapes through the opening 11 while the heavier constituents escape through the opening 10. 30 35 The abrading action of the sides of the plunger compartment 6 upon the edges of the plunger causes a wearing of the outer edges thereof so that it is necessary that the edge portions of the plunger shall be adjusted so as to cause the plunger to effect a closure of the compartment sufficient to cause the necessary movement of water to and fro in the tank 1. 40 45 In so far as I am aware it is novel to provide a plunger for jigs with means whereby its edge portions are automatically adjusted to completely close the compartment in which it operates regardless of its worn condition, provided, of course, it is not completely worn out. In my construction as illustrated in Fig. 1 it will be seen that when the plunger is forced downwardly the water passes through the passage ways 27 and exerts pressure, in proportion to the force with which the plunger is pressed downwardly, against the inner edges of the laterally movable bearing bars 21 so that the outer edges of the said bars are pressed and held firmly against the inside surfaces 50 55 60 of the walls of the compartment in which the plunger operates. It will be understood that these side bars continue to make contact with the inside surfaces of the walls of the compartment independently of their 65 condition of wear until they are completely

worn out. The provision of a construction whereby a plunger automatically adjusts itself to the compartment in which it operates effects great economy by reason of the fact first that the bearing edge portions of the 70 said plunger may be used for a much longer period than has heretofore been possible with the structures in use of which I have had knowledge, and secondly by reason of the fact that economy in operation is secured 75 because it is unnecessary to discontinue operation of the jig from time to time to adjust the edges of the plunger by hand or to substitute new portions for old. 80

When the bearing bars 21 become too much worn to permit of further use they may be removed and new bars substituted by removing the top plate 23. This may be done by removing the top nuts 24. Each of the bolts 25, however, is retained in position by means of the presence of a collar or flange 32 intermediate its ends which is situated in a seat or depression 33 in the upper surface of the plate 12, and a nut 34 connected to the lower end of each of the 90 said bolts. 95

By reason of overlapping the ends of the bearing bars 21 as indicated at 30 it will be readily seen that as the bars become worn and gradually move outwardly very little space is formed at such overlapped ends for the passage of water upwardly beyond the plunger as it is depressed. 95

In Figs. 5 and 6 I have shown a construction of plunger comprising a plate 35 having a recess or hollow 36 upon its under side and also having stiffening or strengthening ribs 37 corresponding substantially to the parts numbered 12, 13 and 16 in Figs. 1 to 4 of the drawings. The outer upper edges of the plate 35 are cut away as indicated at 40 to form seats for the automatically adjustable bearing members of the plunger which will be referred to in detail further on. At the four corners of the plate the upper outer portion thereof is cut away as indicated at 41 so that the surface of the inside wall of the grooves or seats 40 is polygonal in shape. The bearing members consist of the four side bars 42, the opposite ends of which are 110 pointed as indicated at 43. The said pointed ends project into similarly shaped recesses or notches 44 formed upon opposite sides of members 45 which are situated at the corners of the plate 35. The said members 45 are substantially of the shape of an arrow head and the inner ends thereof are located against or in proximity to the parts 41 of the wall at the inner edge of the groove or seat 40. The bearing members 42 and 45 are retained in place in the groove or seat 40 upon the plate 35 by means of a top plate 48 which is secured in position by means of bolts and nuts designated as a whole by the reference numeral 50. The 120 125 130

hollow or recess 36 in the plate 35 is in communication with the groove or seat 40 through the passage ways 51 which terminate adjacent to the inner bearing members 42 and 45 so that as the plunger is moved downwardly the water in the tank passes through the said passage ways 51 and presses against the inner edges of the bearing members 42 and 45 to cause outward movement thereof to hold the same against the sides of the compartment 6. As the parts 42 and 45 become worn and gradually move outwardly away from the vertical shoulder at the inner edge of the groove or seat 40 the extreme pointed ends of the members 42 bear against the surfaces 53 of the members 45 so that only very small openings or passage ways will be formed through which the water may pass upwardly 20 and beyond the plunger as the latter is moved downwardly.

The plate 48 may be removed to permit the removal and replacement of the members 42 and 45 in the same manner as has been described in connection with the members of Figs. 1 and 2 of the drawings.

In Figs. 7 and 8 I have shown a construction of plunger comprising a plate 60 having a hollow or recess 61 in its under side 25 and being provided with strengthening ribs or flanges 62. The outer upper edges of the said plate 60 are provided with grooves 63 in which bearing bars 64 are seated, which bars are adapted to contact with the walls 35 of the compartment in which the plunger is being operated. The plate 60 is cut away at its corners as indicated at 65 forming right angular notches for the reception respectively of one corner of each of the four 40 different guide posts 67 located at the four corners of the said plunger. The opposite ends of the bearing bars 64 rest against sides of the said guide posts 67 as is shown in Fig. 7 of the drawings. The bearing or 45 wearing bars 64 are retained in position upon the plate 60 by means of the plates 69, the inner edges of which are located in depressions or countersinks 70 and the said plates 69 are secured to the plate 60 by means of nuts and bolts 71. The construction of these nuts and bolts is the same as in Figs. 1 to 4 of the drawings.

When a bearing member 64 becomes too much worn for further use it may be removed by removing a plate 69 and substituting a new bearing member for the one removed and then returning and securing the said plate in its original position. The bearing bars 64 are adjustable automatically 55 latterly as is clearly indicated in Figs. 7 and 8 of the drawings so that as they become worn they move outwardly and maintain contact with the walls of the compartment in which the plunger is operating. Passage ways 72 are formed in the plate 60 and ex-

tend from the hollow or recess 61 outwardly and open into the groove 63 in which the bearing members 64 are located. The outer ends of the said passage ways are in proximity to the inner edges of the said bearing members so that when the plunger is moved downwardly the water in the tank passes through the passage way 72 and exerts a pressure or force against the said bearing members to move the same outwardly and hold them against the walls of the plunger compartment. 70

It will be seen that in all of the several forms of construction illustrated the principle of operation is the same and that the changes consist in different details of arrangement. It will also be seen that in the said several forms of construction the bearing members, which also may be termed the wearing members, automatically move outwardly upon the depression of the plunger due to the reacting pressure of the water upon the inner edges of the said bearing members. As a result of such outward movement of the said bearing members the size of the plunger is automatically adjusted as its bearing edges become worn so that it fits accurately and closely the compartment chamber and thus operates efficiently. 80

I claim:—

1. A plunger of the character described comprising a plate-like member having a shouldered recess formed in its outer edge and extending entirely around the same, bearing members situated in the said recess 90 the inner edges of which are adapted to be seated against the said shoulders, and means for loosely holding the said bearing members within the said recess, and the said plate-like member being provided with holes 95 extending from its underneath side and terminating in the shoulders of the said recess for the purpose described. 100

2. A plunger of the character described, comprising a plate like member having a recess in its lower side and having a groove upon the upper side of its outer edge portion and also having passage ways leading from the said recess to the said groove, bearing members movably seated in the said groove 110 and a plate having connection with the first named plate, the edge portions of which plate extend over the said bearing members whereby the latter are retained in position in the said groove, the said bearing members 115 being automatically moved outwardly upon the movement of the said plunger in a direction against a fluid. 120

3. A plunger adapted for use in jigs, which plunger comprises a plate like member having a recess in its lower side, and having a groove in its outer edge portion and also having passage ways leading from the said recess to the said groove, movable bearing members located in the said groove, 125 130

means for retaining the said bearing members in the said groove and permitting the said members to move freely in the direction of the plane of the said plate, the said bearing members being moved automatically outward by fluid pressure exerted against the same through the said openings, and a piston rod for operating the said plunger.

4. A plunger adapted for use in a jig, comprising a main or body member having a recess formed in its lower side, and having a groove formed in its outer edge and also having passage ways leading from the said recess to the said groove, bearing members seated in the said groove, certain of the said members being provided with notches which receive the ends of alternate members as described, and means for retaining the said bearing members in the said groove, the said bearing members being automatically pressed outwardly by fluid pressure exerted upon the edges of the said members when the said plunger is moved in a direction toward the water in the tank of the said jig.

5. A plunger adapted for use in a jig, which plunger comprises a rectangular or a square plate-like member having a recess in its lower side, and having a groove in its edge which groove extends entirely around the edge of the said plate-like member and the material of the said plate-like member being cut away at its four corners whereby the inner wall of the said groove is octagonal in shape and the said plate-like member also having passage-ways from its underneath side which terminate in the shoulders of the said recess, relatively long bearing members situated in the said recess at the side and end edges of said plate-like member and bearing edges interposed between the ends of the said first-named bearing members, the second-named bearing members having notches in their opposite edges for the reception of the ends of the first-named bearing members, means for retaining the said bearing members in position in the said recess, and a piston rod for operating the said plunger, the said bearing members being forced outwardly by fluid pressure exerted against the inside edges thereof when the plunger is forced against the water in the tank of the jig.

6. A plunger adapted for use in a jig, which plunger comprises a rectangular or a square plate-like member having a recess in its lower side, and having a groove in its edge which groove extends entirely around the edge of the said plate-like member and the material of the said plate-like member being cut away at its four corners whereby the inner wall of the said groove is polygonal in shape and the said plate-like member also having passage-ways from the said recess to the said groove, relatively long bearing members located in the said grooves at the side and end edges of the said plate-like member and bearing members interposed between the ends of the first named bearing members, the said second named bearing members having notches in their opposite edges for the reception of the ends of the first named bearing members as de-

scribed, a plate secured to the said plate like member and retaining the said bearing members in position in the said groove, a piston rod for operating the said plunger, the said bearing members being forced outwardly by fluid pressure exerted against the inside edges thereof when the said plunger is forced against the water in the tank of the said jig.

6. A plunger adapted for use in a jig which plunger comprises a rectangular or a square plate-like member having a recess in its edge which recess extends entirely around the edge of the said plate-like member and the material of the said plate-like member being cut away at its four corners whereby the inner wall of the said recess is octagonal in shape and the said plate-like member also having passage-ways from its underneath side which terminate in the shoulders of the said recess, relatively long bearing members situated in the said recess at the side and end edges of said plate-like member and bearing edges interposed between the ends of the said first-named bearing members, the second-named bearing members having notches in their opposite edges for the reception of the ends of the first-named bearing members, means for retaining the said bearing members in position in the said recess, and a piston rod for operating the said plunger, the said bearing members being forced outwardly by fluid pressure exerted against the inside edges thereof when the plunger is forced against the water in the tank of the jig.

In testimony that I claim the foregoing as my invention, I have hereunto signed my name this 23rd day of Jan'y, A. D. 1913.

SAMUEL V. TENCH.
